Primary Examiner — Angela J Lee(74) *Attorney, Agent, or Firm* — Jianq Chyun IP Office**CLAIM**

The ornamental design for a display screen with graphical user interface, as shown and described.

DESCRIPTION

FIG. 1 is a front view showing a first embodiment of a display screen with graphical user interface showing our new design; and,

FIG. 2 is a front view showing a second embodiment of a display screen with graphical user interface showing our new design.

The broken line showing of the display screen in all views illustrates unclaimed environment and forms no part of the claimed design. The broken line showing the remainder of the image in all views illustrates unclaimed portions of the design and forms no part thereof.

The white space within the outer solid line rectangle is claimed.
